UNITED STATES PATENT OFFICE

124,307

DESIGN FOR AN IRONER

Roy A. Dudley and Howard M. Jones, Huntington,
W. Va., assignors to Empire Ironer, Inc., Cincinnati, Ohio

Application March 28, 1940, Serial No. 91,307

Term of patent 7 years

To all whom it may concern:

Be it known that we, Roy A. Dudley and Howard M. Jones, both citizens of the United States and both residing at Huntington, in the county of Cabell and State of West Virginia, have invented a new, original, and ornamental Design for an Ironer, of which the following is a specification, reference being had to the accompanying drawing, forming part thereof.

We claim:

The ornamental design for an ironer, as shown.

ROY A. DUDLEY.

HOWARD M. JONES.
